ALBIN J. NOTT, OF RICHMOND, NEW YORK

SURFACE CONDENSER

Application filed April 3, 1930. Serial No. 441,394.

This invention relates to surface condensers of that type in which a plurality of tubes extend through a condensing chamber and communicate with circulating water boxes located at the opposite ends of the condensing chamber through a pair of tube sheets, each of which defines one wall of said water boxes and one of which tube sheets is fixed while the other is relatively movable to compensate for longitudinal contraction and expansion of the tube.

Condensers of this type now in common use possess certain disadvantages and are open to many objections, notably, if for any reason it becomes necessary to repair or replace one or more of the tubes, the shell or body, as well as the steam, water, condensate and air connections, must be totally or partially disconnected and dismantled, thereby rendering the condenser useless for a considerable period of time.

It is, therefore, one of the principal objects of the present invention to provide a condenser construction by virtue of which the tubes and tube sheets constitute a unit which is readily removable from the body of the condenser without disconnecting any of the shell bolts or the steam, water, condensate or air connections, whereby a substitute or spare unit may be readily inserted within the condenser body while repairs are being made on the removed unit.

The invention further aims to provide in a condenser of this type, tubes which are completely supported and maintained in alignment by the shell of the condenser without employing exterior supports, thereby adapting the condenser for marine as well as other uses.

The invention further aims to provide in a condenser of the type specified, a packing for compensating for the tube expansion, which packing is always in view and subject to frequent inspection and ready repair without the necessity of dismantling the shell.

The invention further aims to provide a condenser the construction of which is not unduly complicated, whereby the same may be inexpensively produced and maintained in proper working order and in fluid tight con-

dition to avoid leakage of the cooling water into the condensing chamber.

With the above recited and other objects in view, reference is had to the following description and accompanying drawings, in which there is exhibited one example or embodiment of the invention, while the claims define the actual scope of the same.

In the drawings:

Figure 1 is a vertical sectional view through a condenser constructed in accordance with the invention.

Figure 2 is a view illustrating the manner in which the tubes and tube sheets may be removed or replaced as a unit.

Figure 3 is a fragmentary vertical sectional view illustrating a slightly modified adaptation of the invention.

Referring to the drawings by characters of reference, 5 designates the condenser shell or body formed at its opposite ends with outwardly projecting annular flanges 6 and 7 and provided intermediate its ends with radially projecting tubular bosses 8, 9 and 10 constituting respectively the exhaust steam inlet, the air removal outlet and the condensate take-off. While the condenser illustrated is of the vertical type and will be described hereinafter as such, it is to be understood that it is not to be restricted to this type but applies to those of the horizontal type also. The condenser further includes a base section 11 which conforms generally to the configuration of the shell 5, and which base section is provided at its upper end with an outwardly extending annular flange 12 and at its lower end with a similar outwardly extending annular flange 13. The base section 11 is provided with a diametrical partition 14 and with a radially projecting tubular inlet boss 15 for receiving the circulating water or cooling fluid. The base section 11 is provided with a diametrically disposed circulating water outlet boss 16. The base section is further provided on opposite sides of the partition 14 with manholes 17 and 18, by virtue of which access may be gained to the interior of the section 11.

In the construction illustrated in Figures 1 and 2, an annulus 19 is interposed between the

flange 7 of the shell 5 and the flange 12 of the base section 11, and said annulus is of a width to present an inwardly projecting annular flange 20. Obviously, in practice, the annulus 19 will be provided on its opposite sides with gaskets 21 and 22 interposed respectively between the annulus and the flanges 7 and 12. The sections, together with the annulus, are secured together by bolts 23. The lower end of the base section is closed by a bottom plate 24 which has interposed between its inner face and the flange 13 a gasket 25. Bolts 26 extend through the bottom plate 24 and the flange 13 and constitute a means for securing the bottom plate to the base section 11.

15 The condenser further comprises a removable unit which includes a fixed tube sheet 30 which is of a diameter to be freely moved axially through the shell 5 from its upper or open end toward its lower or opposite end or vice versa. The fixed tube sheet 30 is of a diameter to rest upon or partially overlap at its outer edge, the inwardly projecting annular flange 20 defined by the annulus 19, and said tube sheet has expanded or otherwise rigidly secured and sealed therein the tubes 31. The opposite ends of the tubes 31 are expanded or otherwise permanently secured in a tube sheet 32 which constitutes one wall 30 of a water box 33 with which all of the tubes communicate through the tube sheet 32. As illustrated in Figures 1 and 2, the tube sheet 32 is formed integral with the annular wall 34 of the water box 33, which wall at its upper 35 or free end is provided with an outwardly projecting annular flange 35, the outer periphery of which corresponds in diameter substantially to the diameter of the end flange 6 of the shell 5. The water box is provided with a cover plate or upper wall 36 which is removably joined to the open end of the water box in any suitable manner, such as by the threaded studs 37 which extend through openings in the outer edge of the cover plate 36 and have engaged thereover nuts 38. A gasket 39 is preferably arranged between the cover plate and the flange 35 to seal the water box 33 against leakage. The cover plate 36 may also be provided with a centrally disposed eye 40, the purpose of which will hereinafter appear. This structure obviously provides a unit which may be readily emplaced in or removed from the shell of the condenser without requiring disconnection of the shell and base section or disconnection of the conduits which are attached to the exhaust steam inlet 8, the air outlet 9, the condensate take-off 10 or the circulating water inlet or outlet.

60 The unit when emplaced in the condenser shell 5 is secured thereto by fastening elements 41, preferably threaded studs carried by the tube sheet 30 and engaged through openings 42 in the inwardly projecting annular flange 20 defined by the annulus 19, after 65 which nuts 43 are applied from within the

base section 11 by operatives who gain access thereto through the manholes 17 and 18. Obviously, this fixedly connects the tube sheet 30 of the unit to the condenser shell. In order to avoid leakage of the steam and condensate from the condensing chamber 45 while permitting the water box 33 sufficient movement with respect to the shell 5 to compensate for the contraction and expansion of the tubes 31, a flexible annulus or tube 46 of rubber or copper is employed, the opposite ends 47 and 48 of which are secured respectively to the flange 6 of the shell and to the flange 35 of the water box 33. As illustrated, the ends 47 and 48 are turned outwardly and clamped between the flanges 6 and 35 respectively and washers 49 and 50 by means of bolts 51 and 52.

70 In operation, it is, of course, apparent that the exhaust steam enters the condensing chamber 45 through the inlet 8 while the cooling or circulating fluid or water enters the base section 11 through the inlet 15, thence flows through the tubes 31 to the water box 33, thence through the remaining set of tubes from the water box 33 to the base section 11 on the opposite side of the partition wall 14 and thence flows outwardly through the outlet 16. The steam is condensed by contact with the tubes 31 in the condensing chamber and the condensate flows or is taken off through the outlet 10 while the air may be removed through the air removal boss 9. Contraction and expansion of the tubes 31 is compensated for by relative movement between the water box 33 and the shell 5 while the flexible tubing 46 serves in the capacity of an expansion joint to prevent the outside air from leaking into the shell 5 when the same is under vacuum and to prevent the steam or condensate from leaking out when the shell 5 is under pressure.

75 In event repairs to the tube sheets, tubes or water box are necessary or replacement of the tubes is required, operatives enter the base section 11 through the manholes 17 and 18 and remove the nuts 43 from the studs 41, thereby releasing the fixed tube sheet 30. The bolts 52 are then removed and by attaching a hoist cable A to the eye 40, it is apparent that the tubes, tube sheet 30 and water box 33 may be withdrawn from the condenser shell as a unit without disturbing any of the shell bolts or the steam, water, condensate or air connections. In practice, in large plants especially, a spare unit or two of this type will be kept on hand for an emergency so that when a damaged unit requires repairs, it is only necessary to remove the damaged unit and replace it with the spare unit while repairs are being effected on said damaged unit. Obviously, this will save considerable time due to the fact that the condenser will only be out of operation for the length of time it requires to remove a damaged unit and replace it with a new one.

After a damaged unit has been removed, the cover plate 36 may be separated from the water box to facilitate the gaining of access to the ends of the tubes in the tube sheet 32. It is also apparent that the tubular packing 46 which allows for the expansion and contraction is always in view, where it is subject to frequent inspection and convenient when repairs or replacement thereof are necessary, 10 without requiring dismantling of the condenser shell.

In the form of the invention illustrated in Figure 3, the condenser shell 5a is provided at its lower end with an integral inwardly extending annular flange 20a, thereby eliminating the separate annulus 19 illustrated in the first form of the invention. In this instance also, the upper end 5b of the condenser shell is of slightly larger diameter than the remainder of the shell and the annular wall 34a of the water box 33a is made as a separate piece from the tube sheet 32a. In this instance, the tube sheet 32a is secured to an inwardly projecting annular flange 34b formed 20 on the wall 34a by means of threaded studs 34c and nuts 34d, a packing 34e being interposed between the flange 34b and the tube sheet 32a. In all other respects, the construction and operation of the condenser is identical with the other form of the invention and in effect is equivalent to said other form illustrated in Figures 1 and 2.

What is claimed is:

1. In a surface condenser, a tubular shell body having flanges at its opposite ends, a fixed section having a closed outer end and a flanged inner end secured to one end of the shell body, an annulus secured between the flanged connected ends of the shell body and fixed section and extending radially inward to constitute an annular seat; and a removable unit including a fixed tube sheet disposed within and detachably connected with the annular seat to define within the fixed section a fixed circulating water box, a movable circulating water box disposed within the opposite open end of the shell body for relative axial movement and having an inner wall constituting a tube sheet and circulating water tubes permanently sealed at their opposite ends in the tube sheets.

2. In a surface condenser, a tubular shell body having flanges at its opposite ends, a fixed section having a closed outer end and a flanged inner end secured to one end of the shell body, an annulus secured between the flanged connected ends of the shell body and fixed section and extending radially inward to constitute an annular seat; and a removable unit including a fixed tube sheet disposed within and detachably connected with the annular seat to define within the fixed section a fixed circulating water box, a movable circulating water box disposed within the opposite open end of the shell body for

relative axial movement and having an inner wall constituting a tube sheet and circulating water tubes permanently sealed at their opposite ends in the tube sheets, said movable water box provided with a flange at its outer end and a flexible tubular sealing element connected at its opposite ends respectively to the flanges of the shell body and movable water box.

Signed at New York city, in the county of New York and State of New York, this 1st day of April, A. D. 1930.
